US0D1033136S

(12) **United States Design Patent** (10) Patent No.: **US D1,033,136 S**
(45) Date of Patent: ** Jul. 2, 2024

(54) **CUTTER BLADE FOR COFFEE GRINDERS**

(71) Applicant: **DAITO GIKEN, INC.**, Tokyo (JP)

(72) Inventor: **Masato Saito**, Tokyo (JP)

(73) Assignee: **DAITO GIKEN, INC.**, Tokyo (JP)

(**) Term: **15 Years**

(21) Appl. No.: **35/517,111**

(22) Filed: **May 9, 2022**

(80) **Hague Agreement Data**

Int. Filing Date: **May 9, 2022**

Int. Reg. No.: **DM/220985**

Int. Reg. Date: **May 9, 2022**

Int. Reg. Pub. Date: **May 12, 2023**

(30) **Foreign Application Priority Data**

Nov. 16, 2021 (JP) ..... 2021-25080 D

(51) **LOC (14) Cl.** **31-00**

(52) **U.S. Cl.**

USPC **D7/414**

(57) **CLAIM**

The ornamental design for a cutter blade for coffee grinders, as shown and described.

DESCRIPTION

1. Cutter blade for coffee grinders

1.1 : Front

1.2 : Back

1.3 : Top

1.4 : Bottom

1.5 : Left

1.6 : Right

1.7 : Perspective

1.8 : Perspective

(Continued)

There are cutter blades on one side of a circular member with a hole in the center.

1 Claim, 8 Drawing Sheets
